(57) **CLAIM**

The ornamental design for a medical monitor, as shown and described.

DESCRIPTION

FIG. 1 is a front elevational view of the medical monitor, with a handle in an opened position, showing our new design, the broken lines are for purposes of illustration only and from no part of the claimed design;

FIG. 2 is a left side elevational view of the medical monitor with the handle in the opened position;

FIG. 3 is a right side elevational view of the medical monitor with the handle in the opened position;

FIG. 4 is a top plan view of the medical monitor with the handle in the opened position;

FIG. 5 is a rear elevational view of the medical monitor with the handle in the opened position;

FIG. 6 is a bottom plan view of the medical monitor with the handle in the opened position;

FIG. 7 is a front perspective view of the medical monitor with the handle in the opened position;

FIG. 8 is a rear perspective view of the medical monitor with the handle in the opened position;

FIG. 9 is a front elevational view of the medical monitor with the handle in a closed position;

FIG. 10 is a left side elevational view of the medical monitor with the handle in the closed position;

FIG. 11 is a right side elevational view of the medical monitor with the handle in the closed position;

FIG. 12 is a top plan view of the medical monitor with the handle in the closed position;

FIG. 13 is a rear elevational view of the medical monitor with the handle in the closed position;

FIG. 14 is a bottom plan view of the medical monitor with the handle in the closed position;

FIG. 15 is a front perspective view of the medical monitor with the handle in the closed position; and,

FIG. 16 is a rear perspective view of the medical monitor with the handle in the closed position.
